Application October 3, 1933, Serial No. 691,938

18 Claims. (Cl. 112—158)

This invention relates to improvements in sewing machines and more particularly in zigzag-stitch sewing machines, although certain features of construction are adapted for employment in straightaway stitching machines.

The primary and general object of the present invention is to provide a simply constructed and readily assembled zigzag-stitch sewing machine adapted for domestic use, as well as for general manufacturing purposes. A more specific object of this invention is to provide a needle-vibrating mechanism of simple construction, so arranged that the amplitude of needle-vibration may be readily controlled and that the needle-vibration may be discontinued to produce straightaway stitches in accurate alinement, whereby the sewing machine is adapted for the ordinary purposes of domestic use and is equally capable of employment for embroidering, eyeletting, darning, etc.

Another object of the invention is to provide for conveniently interchanging throat-plates of a sewing machine to better adapt a straightaway stitching machine for embroidering, darning, etc. The invention has also for its object to provide improved loop-taker and work-feeding mechanism for sewing machines.

With the above and other more specific objects in view, the invention comprises the devices, combinations and arrangements of parts herein-after described in connection with the accompanying drawings which illustrate a preferred embodiment of the invention, from which the several features of the invention and the advantages attained thereby will be readily understood by those skilled in the art.

In the drawings, Fig. 1 is a front side elevation, partly in section, of a sewing machine representing a preferred embodiment of the present invention. Fig. 2 is a rear side elevation, partly in section, of the sewing machine, with the rear bracket-arm wall cover-plate removed. Fig. 3 is a bottom plan view of the sewing machine. Fig. 4 is a front end elevation of the bracket-arm head, with the face-plate removed therefrom, and of the work-support. Fig. 5 is a vertical section of a portion of the bracket-arm standard and of the machine bed-plate, taken transversely of the length of said bed-plate and illustrating the reverse feed actuating and controlling mechanism. Fig. 6 represents a section of the front end portion of the machine bed-plate taken in the vertical plane containing the loop-taker shaft. Fig. 7 represents a section of the front end portion of the machine bed-plate taken in the vertical plane

containing the loop-taker actuating shaft. Fig. 8 represents a section of a portion of the machine bracket-arm, taken substantially in the horizontal plane containing the needle-bar vibrating cam-shaft. Fig. 9 represents a transverse section of the machine bed-plate taken substantially on the line 9—9 of Fig. 3 and illustrating the feed-bar connections. Fig. 10 represents a fragmentary section of the bracket-arm standard taken substantially on the line 10—10 of Fig. 1. Fig. 11 is a top plan view of the throat-plate as employed for zigzag stitching purposes. Fig. 12 is a top plan view of a feed-cover type of throat-plate which may be interchangeably employed with the throat-plate illustrated in Fig. 11. Fig. 13 represents a longitudinal section of the feed-cover type of throat-plate as applied to the machine bed-plate.

Referring to the drawings, the present improvements have been embodied in a sewing machine having a flat bed-plate 1, affording a work-support, and from one end of which rises the hollow standard 2 of a bent bracket-arm 3, overhanging the bed-plate and terminating in a head 4 closed at its outer end by a detachable face-plate 5.

Rotatably journaled in suitable bearings provided in said bracket-arm 3 is a horizontally disposed main shaft 6, extending lengthwise of the bracket-arm and carrying at one end a driving pulley 7. At its opposite end, the main shaft 6 carries a counter-balanced crank 8 provided with a crank-pin 9 connected by a link 10 with a take-up lever 11 suitably fulcrumed within the hollow head 4. Pivotally journaled upon an offset portion of the crank-pin 9 is a split sleeve 12 having depending and spaced ears 13 between which the upper end of a needle-bar reciprocating link 14 is pivotally mounted for swinging movements about an axis transverse to the axis of the main shaft 6. The lower end of said link 14 is similarly pivoted between the upstanding spaced ears 15 of a sleeve 16 journaled upon a stud 17 extending parallel to the main shaft 6 from a collar 18 suitably secured upon a vertically disposed needle-bar 19.

The needle-bar 19 carries at its lower end a needle 20 and is journaled for endwise reciprocation in suitable bearings provided upon a vibratory gate 21. The flattened upper end of the gate 21 is disposed within the vertically slotted lower end of a supporting-member 22 adjustably threaded vertically into the upper wall of the bracket-arm head 4 and otherwise unsecured, said gate 21 being pivotally hung upon a screw- 55

stud 23 horizontally spanning the slot in the supporting member 22 to provide for swinging movements of the gate 21 about a pivotal axis substantially transverse to the axis of rotation 5 of the main shaft 6. The lower end of the gate 21 is slabbed to provide opposed flat walls 24 slidably disposed between guide-walls 25 of a guideway formed by vertically slotting the lower wall of the bracket-arm head 4 in a direction where- 10 by the gate 21 is confined to swinging movements in a vertical plane which, in the present case, also contains the axis of rotation of the main shaft 6 and, as will hereinafter appear, is trans- 15 verse to the direction of feed of the work past the needle.

By pivotally hanging the vibratory gate 21 upon a supporting member 22 which is free to turn, said supporting member will automatically adjust itself angularly to correctly position the 20 fulcrum-axis of the gate 21 transversely of the gate guideway 25 in the bracket-arm head, thereby facilitating manufacture as well as assembly 25 of the parts without binding. The needle-bar 19 is restrained against turning in the gate bearings therefor, in a manner well known in the art, by a split guide-lug 26 on the collar 18, which guide-lug is slidably disposed in a vertical guide-slot 27 provided in the gate 21. As will be readily understood, the pivotal connections for the opposite ends of the needle-bar reciprocating link 14 30 permit the link to accommodate itself to the lateral movements of the needle-bar.

Extending horizontally from the lower end 35 of the vibratory gate 21 in the guideway 25 is an arm 28 of which the free end at the outside of the bracket-arm head carries a pivot-block 29. Embracing the pivot-block 29 is the forked end 40 of a rock-arm 30 depending from the front end of a short rock-shaft 31 disposed horizontally transverse to the main shaft 6 and suitably journaled at the under side of the bracket-arm head 4. Extending upwardly from the rock-shaft 31 at the rearward side of the head 4 is a rock-arm 32 of which the free end is connected by a pivot 45 screw 33 to one end of a pitman 34 disposed horizontally and externally at the rearward side of the bracket-arm 3. The other end of the pitman 34 has a fork or yoke 35 and extends through a slot or opening 36 of a flange 38 at the outward 50 side of the rear wall of the bracket-arm, said flange and a depressed portion 3' of the rearward wall of the bracket-arm within said flange together providing a recess 37 housing the yoked end of the pitman. It will therefore be understood 55 that the yoked end of the pitman is disposed externally rearwardly of the bracket-arm wall 3' constituting the bottom wall of the recess 37. A cover-plate 39 is detachably secured upon the flange 38 in any suitable manner to complete the housing of the yoked end of the pitman, but providing for ready access thereto.

The yoke 35 of the pitman 34 embraces a cam 40 disposed within the recess 37 and externally or rearwardly of the bracket-arm wall 3', said cam having a flange 41 between which and said wall 3' the pitman yoke is laterally confined. The cam 40 is suitably secured upon the rearward end of a cam-shaft 42 journaled in the front and rear walls of the bracket-arm 3 below and horizontally 70 transverse to the main shaft 6. A shaft-collar 43 housed in a recess 44 in the front side of the bracket-arm 3 confines the cam-shaft 42 against endwise movement, said recess 44 being closed by a detachable cover-plate 45. A spiral gear 75 46 carried by the main shaft 6 drives a spiral

gear 47 upon the cam-shaft 42, whereby the latter is rotated at one half the speed of rotation of the main shaft. From the foregoing it will be understood that, during the operation of the machine, the cam 40 vibrates the pitman 34 laterally about the pivot screw 33 and that the needle performs one complete reciprocation for each direction of lateral throw of the pitman. 5

In order to translate the otherwise idle laterally vibratory movements of the pitman 34 into 10 effective endwise reciprocatory movements, to thereby impart swinging movements to the needle-bar gate 21, a guide-roller 48 is suitably secured upon the pitman at its inner side and adjacent to the yoke 35. The guideroller 48 is received in a guideway 49 constituted by a rearwardly open slot formed in the outer or rearwardly exposed face of a guide-head 50 extending into a cavity 51 in the bottom wall 3' of the recess 37. The guideway 49 is segmental, the 20 center of curvature thereof in one position of the guide-head 50 lying in the pivotal axis of the pitman 34 afforded by its pivotal connection 33 with the rock-arm 32.

The guide-head 50 has a hub 52 extending 25 through an aperture 53 in the bottom wall of the bracket-arm cavity 51, said hub being secured by a set-screw 54 upon an adjusting shaft 55 disposed parallel to the cam-shaft 42 and having its longitudinal axis in substantially the horizontal plane containing the axis of rotation of said cam-shaft. The guide-head hub 52 abuts against the end of a bearing bushing 56 suitably secured in the front wall of the bracket-arm 3 and affording a bearing for the adjusting shaft 30 55. Secured by a screw 57 upon the adjusting shaft 55 at the front side of the bracket-arm is a manually operable member in the form of a hand-lever 58 provided in its bearing boss with a segmental flange 59 which may be suitably graduated. Adjacent to the periphery of the graduated flange 59 is a pointer 60 constituted by an ear bent forwardly from the cover-plate 45, the latter being suitably apertured to receive the forwardly projecting end of the adjusting 45 shaft 55. The throw of the hand-lever 58 is limited in one direction by a stop-screw 61 adjustably fixed in an apertured ear 62 of the cover-plate 45 to locate the guide-head 50 in its zero position, i. e., to position the guide-head so that its curved 50 guideway 49 is concentric to the pivot screw 33 of the pitman 34, whereby the pitman may perform idle lateral vibrations and the needle-bar gate 21 remains absolutely stationary during the 55 operation of the machine. Movement of the hand-lever 58 away from its zero position is adjustably limited by an opposed stop-screw 63 threaded into another ear 64 of the cover-plate 45. It will be understood that when the hand-lever 58 is moved from its zero position toward the stop-screw 63, the guide-head 50 is angularly adjusted into a position such that, during the operation of the machine, the travel of the 60 guide-roller 48 in the guideway 49 effects endwise reciprocation of the pitman 34, thereby imparting laterally vibratory movements to the needle-bar gate 21. A friction washer 65 is preferably interposed between the hand-lever 58 and the cover-plate 45 to frictionally retain the guide-head 50 in any position into which it is angularly turned by manipulation of the hand-lever 58. 70

It will be evident to those skilled in the art that the described needle-vibrating mechanism is not only simple and sturdy in construction, but 75

that the parts thereof may be readily assembled and suitably timed. The disposition of the pitman actuating cam 40 and guide-head 50 externally of the bracket-arm, with the guideway 49 opening outwardly, provides for conveniently applying the pitman 34 thereto. Furthermore, the housing of the pitman actuating elements in the recess 31 which is formed by the inwardly depressed bracket-arm wall 3' and the arm flange 38 obviates undesirable projection of actuating mechanism and unsightly protuberances upon the bracket-arm. Nevertheless, ready access to said parts within the recess 31 is afforded by the removable cover-plate therefor.

15 The usual spring depressed presser-bar 66 is journaled for vertical movement in the bracket-arm head 4, said presser-bar detachably carrying at its lower end a presser-foot 67 which may be of any suitable construction. The presser-bar 20 may be manually raised, as by means of a hand lifter lever 68, to lift the presser-foot above the work-support for insertion and removal of work.

Cooperating with the needle 20 below the work-support is a loop-taker 69 of the horizontal-axis 25 rotary hook type and of well-known construction, in which hook is journaled a thread-case 70 containing a bobbin or mass of under thread around which the needle-thread loops are cast in the formation of lock-stitches. To better accommodate 30 cooperation with the needle 20 in different paths of reciprocation of the latter, the loop-taker is supported for rotation in a vertical plane parallel to the plane of needle-vibration, and to provide for convenient replenishment of the lower thread the 35 loop-taker is arranged with its open side directed forwardly toward the front of the machine. With these objects in view, the loop-taker 69 is disposed rearwardly of the vertical plane of needle-vibration and is secured upon a loop-taker shaft 71 40 extending horizontally rearwardly from the loop-taker and with its axis of rotation transverse to the plane of needle-vibration. The loop-taker shaft 71 is journaled in spaced bearing bushings 72 and 73 suitably fixed in lugs depending from 45 the bed-plate 1, a collar 74 fastened upon the shaft 71 between said bushings serving to restrain said shaft against endwise movement.

Carried by the loop-taker shaft 71 and disposed 50 adjacent to the loop-taker 69 is a spiral driven gear 75 engaged by a spiral driving gear 76 carried by one end of a horizontal loop-taker actuating shaft 77 disposed below and transversely of the loop-taker shaft 71. The gears 75 and 76 are so designed that the loop-taker shaft is rotated 55 twice for each rotation of the actuating or driving shaft 77. One end of the loop-taker actuating shaft 77 is rotatably journaled in a bearing bushing 78 fixed in a lug 79 depending from the bed-plate 1, said bushing 78 projecting beyond the lug 79 into close proximity to the hub of the driving gear 76. Adjacent to its other end, the loop-taker actuating shaft 77 is suitably journaled in a bearing lug 80 depending from the bed-plate 1, and carries a grooved belt pulley 81 connected 60 by a clip-belt 82, within the arm standard 2, with a pulley 83 upon the main shaft 6. The shafts 6 and 77 rotate in one-to-one relationship. Because of the disposition of the spiral driving gear 76 below the driven gear 75, and the described 65 arrangement of the loop-taker, the loop-taker actuating shaft 77 is spaced substantially below the work-support and rearwardly of the median width thereof, i. e., the loop-taker actuating shaft is disposed rearwardly of a vertical plane containing the axis of rotation of the main shaft 6.

The loop-taker driving gears 75 and 76 are housed in a gear casing having a bearing boss 84 detachably secured by a screw 85 upon the bearing bushing 78, said casing having an annular wall 86 surrounding the driving gear 76 and providing a lubricant chamber 87 which is closed at its outer end by a detachable cover-plate 88. Integral with said casing and disposed above the chamber 87 is a cylindrical band 89 surrounding the driven gear 75 and serving as a guard 10 therefor, the upper portion of the annular wall 86 of the casing (as shown in Fig. 6) being partly cut away to provide clearance for the intermeshing portions of said gears.

The present machine has a reverse feed mechanism adapted to advance the work, selectively in either of opposite directions, in a line transverse to the plane of needle-vibration. This feeding mechanism includes a feed-dog 90 of the lower four-motion type and operating within feed-slots 20 91 (Fig. 11) of a throat-plate 92 which may have a needle-aperture in the form of a slot 93 elongated in the direction of needle-vibration or, if preferred, may be in the form of the usual round aperture when the machine is employed for 25 straightaway stitching. The throat-plate 92 comprises a combination of the usual slide-plate and throat-plate heretofore commonly employed and is so constructed and arranged as to be readily interchangeable with other throat-plates more 30 particularly adapted for special operations such as for embroidering, darning, eyeletting, etc. For this purpose, the throat-plate 92 is formed with parallel side edges 94 merging into a rounded end 95 opposite to a straight-edge end 96 adapted to 35 coincide with the front-end edge 97 of the work-support 1. The work-support 1 is provided with an opening 98 corresponding to the described shape of but slightly smaller than the throat-plate, said opening extending inwardly from the 40 edge 97 of the work-support crosswise of the line of feed and exposing the loop-taker 69 and feed-dog 90. Along the side edges and rounded end of the opening 98, the work-support 1 is provided in its upper face with an upwardly open recessed 45 guideway 99 affording a seat for and confining the throat-plate 92 against movement in the plane thereof, excepting toward the work-support edge 97. Releasable locking means is provided to normally anchor the throat-plate against 50 movement from operative position in the plane of the work-support, said locking means in the present instance consisting of a locking-pin 100 depending from the throat-plate at the rounded end thereof and adapted to enter an aperture 101 55 in the work-support. Suitably secured to the under side of the throat-plate 92, adjacent to the straight end 96 thereof, is a member 102 from which extend oppositely directed spring-wings 103 comprising underhung spring means adapted to slidably engage the beveled under side of the work-support 1 and yieldingly confine the throat-plate to sliding movements in the guideway 99. By pressing upwardly against the under side of the throat-plate 92 adjacent to the 60 feed-dog 90, the throat-plate may be tilted slightly upwardly against the yielding action of the spring-wings 103 to raise the rounded end 95 of said throat-plate sufficiently to withdraw the locking-pin 100 from the aperture 101 and to 65 clear the feed-dog 90. The throat-plate is now free to be slidably removed from the guideway 99 to provide for access to the loop-taker and feed-dog and primarily for substituting another throat-plate therefor. It will be observed that 70 75

the present throat-plate expedient obviates the necessity of removing securing screws therefor and that the interchanging of throat-plates is thereby facilitated as well as by combining the throat-plate and the usual slide-plate heretofore commonly employed.

Figs. 12 and 13 of the drawings illustrate a substitute throat-plate 104 which is particularly adapted for embroidering and darning purposes.

- 10 It will be observed that the throat-plate 104 differs from the throat-plate 92 primarily in omitting the feed-slots of the latter, and in being formed with an annular raised portion 105 having a substantially central needle-aperture 106. 15 The raised portion 105 of the throat-plate serves as a cover for the feed-dog 90, to provide for manually manipulating the work for embroidering or darning purposes. Obviously, other substitute throat-plates may be employed, as for instance plates provided with eyelet-spurs.

20 The feed-dog 90 overhangs the loop-taker 69 and extends laterally from one end of a feed-bar 107 of which the opposite end is pivotally secured to a feed-rocker comprising spaced upstanding arms 108 and 109 of a horizontally disposed feed-advance rock-shaft 110. The rock-shaft 110 is substantially parallel to the loop-taker actuating shaft 71, being journaled beneath the work-support 1 adjacent to the front edge thereof and 25 in suitable bearing lugs 111 and 112. The feed-rocker portion 110' of the feed-advance rock-shaft 110 is bent upwardly from adjacent to the bearing lug 111, said feed-rocker portion of the shaft 110 terminating at one side of a vertical plane containing the line of feed through the 30 needle-aperture in the throat-plate. The described feed-rocker arrangement provides hand clearance for more conveniently replenishing the lower thread supply.

- 35 40 Adjacent to the bearing lug 112, the feed-advance rock-shaft 110 carries an upwardly extending crank-arm 113 to which is pivotally connected one end of a radius-bar 114 of which the forked other end pivotally carries a stud 115. The 45 pivot-stud 115 is apertured transversely of its pivotal axis to slidably engage an upright guide in the form of a rod 116 secured at its opposite ends to spaced ears 117 bent laterally from a rocking frame 118 disposed entirely below the 50 horizontal plane of the work-support 1. The rocking frame 118 is secured upon a short rock-shaft 119 to provide for said frame a fulcrum axis passing transversely through the guide-rod at substantially the middle point of the length of 55 said rod, said rock-shaft 119 being journaled in suitable bearing lugs below the work-support 1 so as to be disposed in parallelism with the feed-advance rock-shaft 110 and at the side of a vertical plane through the axis of the loop-taker 60 actuating shaft 71 opposite to that of the rock-shaft 110. The rocking frame 118 has a fork 120 embracing a cam or eccentric 121 carried by the loop-taker actuating shaft 71 to impart the feed-advancing and return movements to the feed-dog 90.

65 The radius-bar 114, intermediate its ends, is provided with a laterally extending boss 122 to which is pivotally connected the lower end of a link 123 extending upwardly through an opening in the bed-plate 1 and into the bracket-arm standard 2. At its upper end, the link 123 is pivotally connected to a feed-adjusting lever 124 extending transversely of the standard 2 from rear to front and being fulcrumed upon a pivot-screw 125 in the rear wall of said standard 2.

70 The front end of the feed-adjusting lever extends through a slot 126 in the front wall of the standard 2 and is threaded to receive a nut or manipulating head 127. The head 127 is socketed in its inner face to slidably receive a sleeve 128 within which is disposed a coil-spring 129 reacting against the head 127 and a transverse web 130 within the sleeve 128. The inner end of the sleeve 128 is partly cut away to provide vertically spaced guide-lugs 131 slidably disposed in a vertical slot 132 formed in a graduated segment-plate 133, said segment-plate being secured by screws 134 to a boss 135 upon the front wall of the arm-standard 2. A pointer 136 is carried by the sleeve 128 to overlie the graduations of the segment-plate 133. The frictional engagement of the sleeve 128 with the front face of the segment-plate 133 permits of manually shifting the feed-adjusting lever 124 vertically, but is effective to hold said lever in adjusted position without requiring tightening of any securing nuts heretofore commonly employed.

75 Secured by screws 137 upon the feed-adjusting lever 124 within the standard 2 is a block 138 carrying at one side thereof a projection 139 provided with a recess 140 of horizontal V-shape disposed in a vertical plane inclined to the feed-adjusting lever 124 and open toward the front of the bracket-arm. Adjustably entering the V-shaped recess 140 is the rounded end of a 80 stop-screw 141 threaded through the front wall of the arm-standard 2 at an inclination to the feed-adjusting lever 124 and having a manipulating head 142 at the outer side of the arm standard.

85 From the foregoing description, it will be understood that in the zero or median position of throw of the feed-adjusting lever, the axis of the radius-bar pivot-stud 115 coincides with the fulcrum-axis 119 of the rocking frame 118 and 40 accordingly the feed-dog 90 is then stationary as to work-advancing movements during the operation of the machine. Movement of the feed-adjusting lever out of its zero position in either direction is adjustably limited by the stop-screw 45 141, it being understood that in any set position of the stop-screw 141 the feed-adjusting lever is definitely limited to movements of equal extent in opposite directions from its zero position. As the pivot-stud 115 of the radius bar 114 is shifted 50 either above or below the fulcrum-axis 119 of the rocking frame 118 according to the direction of movement of the feed-adjusting lever out of its zero position, it is apparent that the direction and amplitude of work-advancing movements of 55 the feed-dog may be readily controlled.

60 Rising and falling movements are imparted to the feed-dog 90 from a feed-lift cam 143 carried by the loop-taker actuating shaft 71 adjacent to the bed-plate lug 79, said cam 143 being embraced by the forked end of a rock-arm 144 extending forwardly from said cam. The other end of the rock-arm 144 is suitably secured upon a short feed-lift rock-shaft 145 journaled beneath the work-support 1 in parallelism with the feed-advance rock-shaft 110 and between said rock-shaft 110 and the loop-taker actuating shaft 71. Extending rearwardly from the feed-lift rock-shaft 145, adjacent to the feed-bar 107, is a feed-lift arm 146 provided at one side thereof with 70 a stud 147 carrying a roller 148 received in a horizontal slot 149 provided in the feed-bar 107.

75 The arrangement of the reverse-feed actuating mechanism entirely below the work-support not only minimizes vibration during the operation 75

of the machine, but very materially facilitates assembly and adjustment of the parts. Furthermore, the disposition of the feed-lift rock-shaft 145 at the same side of the loop-taker actuating shaft 77 as the feed-advance rock-shaft 110 provides for employing a comparatively short and therefore rigid feed-lift rock-arm 146 and a comparatively large feed-lift cam 143 upon the loop-taker shaft 77, said large cam 143 minimizing inaccuracies due to wear and the short rock-arm 146 insuring a positive unyielding lift of the feed bar. As will be evident, the described construction is particularly favorable in combination with the loop-taker mechanism described, because it permits of the disposition of the bearing lug 78 close to the vertical transverse plane containing the axis of rotation of the loop-taker shaft 77, thereby affording a firm support for the gear-carrying end of the shaft 77 and also providing supporting means for the gear casing secured upon the bushing 79, all without interfering with the feeding mechanism and ready assembly of the parts. The location of the fulcrum shaft 119 of the feed-actuating rocking frame 118 at the side of the shaft 77 opposite to the feed-advance rock-shaft 110 side thereof permits of employing a comparatively long radius bar 114 which facilitates adjustment of the direction and amplitude of feed-advance movement of the feed-dog. It will therefore be apparent that the present feeding mechanism is simple in construction and that it is particularly well adapted for employment in a machine having a loop-taker mechanism as hereinbefore described.

Having thus set forth the nature of the invention, what I claim herein is:—

1. A sewing machine having a hollow bracket-arm terminating at its free end in a head, a vibratory needle-bar gate mounted in said bracket-arm head, a yoked pitman disposed externally at the rear side of said bracket-arm and extending toward said head, operative connections between said pitman and needle-bar gate including a pivotal support for the end of the pitman adjacent to said head, a cam disposed externally of the rear wall of said bracket-arm in operative engagement with a yoke at the other end of said pitman to impart lateral vibratory movements thereto about said pivotal support, a rotary shaft disposed crosswise of said bracket-arm and carrying said cam, means for rotating said shaft, and means for translating the lateral vibratory movements of the pitman into endwise needle-bar vibrating movements including, a pitman-guide disposed externally of the rear wall of the bracket-arm, and a manually operable adjusting member at the front side of said bracket-arm operatively connected to said pitman guide.

2. A sewing machine having a hollow bracket-arm terminating at its free end in a head, a vibratory needle-bar gate mounted in said bracket-arm head, a yoked pitman disposed externally at the rear side of said bracket-arm and extending toward said head, operative connections between said pitman and needle-bar gate including a pivotal support for the end of the pitman adjacent to said head, a cam disposed at the rear side of said bracket-arm in operative engagement with a yoke at the other end of said pitman to impart lateral vibratory movements thereto about said pivotal support, a rotary shaft disposed crosswise of said bracket-arm and carrying said cam, means for rotating said shaft, and means for translating the lateral vibratory move-

ments of the pitman into endwise needle-bar gate vibrating movements including, an angularly adjustable guide-head disposed at the rear side of said bracket-arm engaged by said pitman, an adjusting shaft journaled in said bracket-arm substantially parallel to the cam shaft and carrying said guide-head, and a manually operable member carried by said adjusting shaft at the front side of said bracket-arm.

3. A sewing machine having a hollow bracket-arm terminating at its free end in a head, a vibratory needle-bar gate mounted in said bracket-arm head, a yoked pitman disposed externally at the rear side of said bracket-arm and extending toward said head, operative connections between said pitman and needle-bar gate including a pivotal support for the end of the pitman adjacent to said head, a cam disposed at the rear side of said bracket-arm in operative engagement with a yoke at the other end of said pitman to impart lateral vibratory movements thereto about said pivotal support, a rotary shaft disposed crosswise of said bracket-arm and carrying said cam, means for rotating said shaft, and means for translating the lateral vibratory movements of the pitman into endwise needle-bar gate vibrating movements including, an angularly adjustable guide-head disposed at the rear side of said bracket-arm and provided with a segmental guide-way having the axis of pivotal support of the pitman as its center of curvature, a pitman carried member engaging said guideway, and manually operable means for angularly adjusting said guide-head.

4. A sewing machine having a hollow bracket-arm terminating at its free end in a head, a vibratory needle-bar gate mounted in said bracket-arm head, a yoked pitman disposed externally at the rear side of said bracket-arm and extending toward said head, operative connections between said pitman and needle-bar gate including a pivotal support for the end of the pitman adjacent to said head, a cam disposed at the rear side of said bracket-arm in operative engagement with a yoke at the other end of said pitman to impart lateral vibratory movements thereto about said pivotal support, a rotary shaft disposed crosswise of said bracket-arm and carrying said cam, means for rotating said shaft, and means for translating the lateral vibratory movements of the pitman into endwise needle-bar gate vibrating movements including, an angularly adjustable guide-head disposed at the rear side of said bracket-arm, said guide-head being provided at its exposed side with a guideway engaged by said pitman, and manually operable means accessible from the front of said bracket-arm for angularly adjusting said guide-head.

5. A sewing machine having a hollow bracket-arm terminating at its free end in a head a vibratory needle-bar gate mounted in said bracket-arm head, a yoked pitman disposed externally at the rear side of said bracket-arm and extending toward said head, operative connections between said pitman and needle-bar gate including a pivotal support for the end of the pitman adjacent to said head, a cam disposed at the rear side of said bracket-arm in operative engagement with a yoke at the other end of said pitman to impart lateral vibratory movements thereto about said pivotal support, a rotary shaft disposed crosswise of said bracket-arm and carrying said cam, means for rotating said shaft, and means for translating the lateral vibratory movements

of the pitman into endwise needle-bar gate vibrating movements including, an angularly adjustable guide-head disposed at the rear side of said bracket-arm and provided with a segmentally curved guide-slot, a stud carried by said pitman and disposed in said guide-slot, an adjusting shaft journaled in said bracket-arm substantially parallel to the cam shaft and carrying said guide-head, and a manually operable member carried by said adjusting shaft at the front side of said bracket-arm.

6. A sewing machine having a hollow bracket-arm terminating at its free end in a head, a vibratory needle-bar gate mounted in said bracket-arm head, a yoked pitman disposed externally at the rear side of said bracket-arm and extending toward said head, operative connections between said pitman and needle-bar gate including a pivotal support for the end of the pitman adjacent to said head, a cam disposed at the rear side of said bracket-arm in operative engagement with a yoke at the other end of said pitman to impart lateral vibratory movements thereto about said pivotal support, a rotary shaft disposed crosswise of said bracket-arm and carrying said cam, means for rotating said shaft, and means for translating the lateral vibratory movements of the pitman into endwise needle-bar gate vibrating movements including, an angularly adjustable guide-head disposed at the rear side of said bracket-arm, said guide-head having at its rear outer side a vertically-disposed segmentally curved guide-slot, a stud carried by said pitman and disposed in said guide-slot, an adjusting shaft journaled in said bracket-arm substantially parallel to the cam-shaft and carrying said guide-head, and a manually operable member carried by said adjusting shaft at the front side of said bracket-arm.

7. A sewing machine having a hollow bent bracket-arm formed with a recess in its rear wall adjacent the bend in said bracket-arm, a main-shaft journaled horizontally in said bracket-arm, a rotary cross-shaft journaled in said bracket-arm and geared to be driven by the main-shaft at half the speed of the latter, said cross-shaft having a cam fixed to its rearward end at the outer side of said bracket-arm and within said recess, a manually operable oscillatory adjusting shaft journaled in said bracket-arm in parallelism with said rotary cross-shaft and projecting at its forward end through the front wall of said bracket-arm, a guide-head formed with a rearwardly open guide-slot fixed to the rearward end of said adjusting shaft at the outer side of said bracket-arm within said recess, a removable cover-plate closing said recess, a yoked pitman embracing said cam and having a guide-stud disposed in the slot of said guide-head, said pitman extending under said cover-plate and thence externally and in rear of the bracket-arm toward the free end of the latter, and a vibratory needle-bar gate connected to be actuated by said pitman.

8. In a needle-bar vibrating mechanism for sewing machines, the combination with a hollow sewing machine bracket-arm formed with a standard and an overhanging arm terminating in a head, the rear wall of said bracket-arm having a rearwardly extending slotted flange providing a housing recess, a removable cover-plate for said recess, a vibratory needle-bar gate mounted in said head, a pitman extending lengthwise and externally of said overhanging arm in rear of the latter and connected at one end to vibrate said gate, the other end of said pitman

having a yoke extending under said cover-plate through the slot of said recess, an actuating shaft, and means connected to said actuating shaft for operating said pitman, said means comprising a rotary cam embraced by the yoked end of said pitman, a guide-head having a rearwardly open guide-slot engaged by said pitman and concealed by said cover-plate, an adjustable cross-shaft carrying said guide-head and projecting through the front wall of the bracket-arm, and a manually operable member secured to the front end of said cross-shaft.

9. A sewing machine having a hollow bent bracket arm having a portion of its rear wall adjacent to the bend of the bracket-arm inwardly depressed to form an external housing-recess in said bracket-arm, said depressed portion of the bracket-arm wall being provided with a cavity, an actuating shaft journaled in said bracket-arm, a rotary cross-shaft journaled in the front and rear walls of said bracket-arm and geared to be driven by said actuating shaft at half the speed of the latter, a cam fixed upon the rearward end of said cross-shaft and housed within said recess of the bracket-arm, an angularly adjustable guide-head extending into the cavity in said depressed wall of the bracket-arm, said guide-head being provided at its exposed rearward side with a guideway, a removable cover-plate closing said recess, a yoked pitman embracing said cam and engaging said guideway, said pitman extending under said cover-plate and thence externally and in rear of the bracket-arm toward the free end of the latter, and a vibratory needle-bar gate connected to be actuated by said pitman.

10. A sewing machine having a bracket-arm provided with housing-recesses in the outer faces of the front and rear walls thereof, removable cover-plates for said recesses, a rotary actuating shaft journaled in said bracket-arm, a rotary cross-shaft journaled in the front and rear walls of said bracket-arm and geared to be driven by said actuating shaft, said cross-shaft extending at its opposite ends into said recesses, a shaft-positioning member carried by said cross-shaft and housed within the front wall recess of the bracket-arm, a cam carried by said cross-shaft and housed within the rear wall recess of the bracket-arm, a yoked pitman embracing said cam and deriving laterally vibratory movements therefrom, a vibratory needle-bar gate mounted in said bracket-arm, an angularly adjustable pitman-guide for translating the laterally vibratory movements of said pitman into endwise reciprocatory movements thereof, and connections for transmitting the endwise reciprocatory movements of the pitman to said needle-bar gate.

11. A sewing machine having a bracket-arm, a rotary actuating shaft journaled in said bracket-arm, a rotary cam-shaft journaled in said bracket-arm extending transversely of and geared to be driven by said actuating shaft, a flanged cam carried by said cam-shaft externally of the rear wall of said bracket-arm, a pitman having a yoke embracing said cam and deriving laterally vibratory movements therefrom, said pitman being confined by the flange of said cam against movement in one direction axially of said cam-shaft, means including a pitman-guide for translating the laterally vibratory movements of said pitman into endwise reciprocatory movements thereof, and a vibratory needle-bar gate connected to be actuated by said pitman.

12. A sewing machine having a bracket-arm provided in the front wall thereof with a recess, a

- rotary actuating shaft journaled in said bracket-arm, a rotary cam-shaft journaled in said bracket-arm extending transversely of and geared to be driven by said actuating shaft, a collar carried by said cam-shaft within said front wall recess of the bracket-arm, a cam carried by said cam-shaft, a pitman having a yoke embracing said cam and deriving laterally vibratory movements therefrom, an angularly adjustable pitman-guide for translating the laterally vibratory movements of said pitman into endwise reciprocatory movements thereof, a vibratory needle-bar gate, connections for transmitting the endwise reciprocatory movements of the pitman to said gate, an adjusting shaft for said pitman-guide, said adjusting shaft being journaled in said bracket-arm in parallelism to said cam-shaft, a hand lever carried by said adjusting shaft at the front side of said bracket-arm and provided with a graduated segment, a cover-plate for said bracket-arm recess removably secured upon the bracket-arm, said cover-plate carrying an indicating pointer adjacent to the graduated segment of said lever, and opposed stop screws adjustably carried by said cover-plate to limit movement of said hand-lever in opposite directions.
13. In a sewing machine, a bracket-arm, a supporting member mounted in said bracket-arm for turning movement, a pendulous needle-bar gate hung upon said supporting member for swinging movements about an axis transverse to the axis of turning movement of the supporting member, stationary guide walls spaced from said supporting member for directionally controlling said swinging movements of the needle-bar gate, and means for imparting swinging movements to said gate.
14. In a sewing machine, a bracket-arm, a supporting member mounted in said bracket-arm for angular adjustment about an axis, a pendulous needle-bar gate hung upon said supporting member for swinging movements about an axis transverse to the axis of angular adjustment of said supporting member, and guiding
- means for said gate controlling angular adjustment of said supporting member to thereby accurately position the pivotal axis of said gate.
15. In a sewing machine, a bracket-arm, a supporting member adjustably threaded into said bracket-arm, a pendulous needle-bar gate hung at its upper end upon said supporting member for swinging movements about an axis transverse to the direction of the length of said supporting member, guiding means below said supporting member for said needle-bar gate, and means for imparting swinging movements to said gate.
16. In a sewing machine, a horizontally disposed work-support, a bracket-arm overhanging said work-support, a supporting member adjustably threaded vertically into said bracket-arm and free to turn about a substantially vertical axis, a pendulous needle-bar gate hung at its upper end upon said supporting member for swinging movements about a substantially horizontal axis, guiding means for directionally controlling said swinging movements of the needle-bar gate, and means for imparting swinging movements to said gate.
17. In a sewing machine, a bracket-arm terminating at its free end in a head formed with a vertical guide-slot, a vertically slotted supporting-member mounted in said head for turning movement about a vertical axis, a pendulous needle-bar gate pivotally mounted in the slot of said supporting member and slidably disposed in said guide-slot, and means for imparting swinging movements to said gate.
18. In a sewing machine, a bracket-arm terminating at its free end in a head, a supporting member adjustably threaded into said head, a pendulous needle-bar gate pivotally hung upon said supporting member for swinging movements about an axis transverse to the thread axis of said supporting member, means restraining said supporting member against turning movement, and means for imparting swinging movements to said gate.

GEORGE M. EAMES.
